UNITED STATES PATENT OFFICE.

JOHN T. HENDERSON, OF CATSKILL, NEW YORK.

DESIGN FOR A SPOON.

SPECIFICATION forming part of Design No. 21,283, dated January 5, 1892.

Application filed November 25, 1891. Serial No. 413,146. Term of patent 7 years.

To all whom it may concern:

Be it known that I, JOHN T. HENDERSON, a citizen of the United States, residing at Catskill, in the county of Greene and State of New York, have invented a new and original Design for Spoons, of which the following is a specification.

The invention relates to a new and original design for handles of spoons, forks, button-hooks, and similar articles.

The object of the present invention is to provide for handles of spoons, forks, button-hooks, and analogous articles a design which will render them ornamental and attractive.

The leading feature of my design for a handle of spoons, forks, and the like consists in a representation of a scene in the Catskill mountains emblematic of the legend of "Rip Van Winkle," a representation of the Kaaterskill Falls, and the ornamentation around the representations.

In the accompanying drawings, Figure 1 shows the front, and Fig. 2 shows the back, of a spoon ornamented with my original design.

In the drawings is illustrated a spoon pro-

vided on the front face of the handle with a representation of a scene in the Catskill mountains emblematic of the legend of "Rip Van Winkle," and showing him before his twenty-years' sleep in apparent conversation with the dwarf, and supporting his gun with one hand and accompanied by his dog. This representation is accompanied by ornamental foliage and scrolls.

On the reverse side of the handle of the spoon is a representation of a scene in the Catskill mountains, showing the Kaaterskill Falls. This representation is accompanied by ornamental foliage and scrolls.

What I claim is—

The design for the handles of spoons, forks, &c., as herein shown and described.

In testimony that I claim the foregoing as my own I have hereto affixed my signature in the presence of two witnesses.

JOHN T. HENDERSON.
